UNITED STATES PATENT OFFICE

120,011

DESIGN FOR AN IDENTIFICATION TAG

William R. Knight, Spartanburg, S. C.

Application February 5, 1940, Serial No. 90,051

Term of patent 3½ years

To all whom it may concern:

Be it known that I, William R. Knight, a citizen of the United States, residing at Spartanburg, in the county of Spartanburg and State of South Carolina, have invented a new, original, and ornamental Design for an Identification Tag, of which the following is a specification, reference being had to the accompanying drawing, forming a part thereof.

In the drawing:

The dominant features of my design are shown in full lines in the drawing.

I claim:

The ornamental design for an identification tag, as shown and described.

WILLIAM R. KNIGHT.
